UNITED STATES PATENT OFFICE.

HERMAN L. WAGNER, OF MOUNT VERNON, NEW YORK, ASSIGNOR TO UNDERWOOD TYPE-WRITER COMPANY, OF NEW YORK, N. Y., A CORPORATION OF NEW JERSEY.

TYPE-WRITING MACHINE.

No. 904,029.

Specification of Letters Patent.

Patented Nov. 17, 1908.

Application filed October 13, 1906. Serial No. 338,859.

To all whom it may concern:

Be it known that I, HERMAN L. WAGNER, a citizen of the United States, residing in Mount Vernon, in the county of Westchester and State of New York, have invented certain new and useful Improvements in Type-Writing Machines, of which the following is a specification.

This invention relates principally to that 10 class of tabulating mechanisms for type-writing and other machines in which independently operable denomination keys are provided, although certain features thereof may be applied to other tabulating mechanisms.

My invention is in the nature of an improvement upon the construction shown in my pending application No. 323,588 (Patent No. 853,280), in which the denomination keys 20 are shown mounted in a row on the ends of short arms which extend forwardly from the front bar of the paper carriage, denomination stops being rigidly connected to said arms and depressible independently one of 25 another by the keys to engage column stops and placed side by side at letter space intervals, and each key arm with its stop forming a bail, the bails being of graduated sizes and nested together in two sets, and key 30 bearing arms diverging or fanning out at each side of the set of stops to compensate for the greater length of the rows of keys.

One object of the invention is to improve and simplify the form and nesting of the 35 bails and to avoid faulty action thereof upon the depression of the keys. I place all of the keys directly upon the stop-arms, so that in each of the two sets of bails are comprised a large bail carrying a key upon its stop-arm 40 and successively smaller bails within said larger bail and forming a regular nest, each stop-arm carrying a key. The keys are carried upon extensions which diverge to the right and left of the stop-arms, and means 45 are added directly beneath the keys for arresting them to avoid distortion of the bails in action.

In the preferred form of the present invention one or more stops are introduced 50 between the two sets of bails to further simplify the construction and economize room; said additional stop-arms being single arms and pivoted upon a common axis of the bails and carrying keys at their forward ends.

55 In the accompanying drawings, Figure 1

is a plan of the front upper portion of an "Underwood" typewriting machine provided with my improvements in their preferred form. Fig. 2 is a sectional side elevation illustrating the operation of setting a 60 denomination key and simultaneously releasing the carriage. Fig. 3 is a perspective view of two of the denomination-keys and stops. Fig. 4 is a diagram showing the same arrangement of denomination mechanism, as at Fig. 1, and showing the two 65 middle stop-arms as lengthened and formed into bails.

The usual cylindrical platen is illustrated at 1, and is mounted upon a shifting platen 70 frame, (not shown), the latter mounted in the usual manner upon a carriage comprising side bars 2 and front bar 4. The carriage is propelled by the usual spring barrel 5 and strap 6, and is provided with a letter spacing rack 7 to mesh with a pinion 8, the latter forming part of the usual escapement or letter feeding mechanism. Said rack is usually provided at its ends with a 75 pair of arms 9 hinged at 10 upon the carriage frame and provided with a forwardly extending depressible arm 11, so that by depressing the arm, the rack may be raised clear of the pinion 8, and the carriage may run along freely under the influence of the 80 propelling spring 5. The carriage has a front roll 13 running upon a track 14.

Extending along the carriage in front of the platen is a horizontal rock shaft 15 mounted in ears 16 projecting from a bracket 90 17, the latter detachably secured by screws 18 upon the top of the front carriage bar 4. Said rock shaft extends through the end bar 2 of the carriage and is provided with a short arm 19, to vibrate a lever 20, and 95 thereby depress the arm 11 of the rock frame 7, 9, and release the carriage. A carriage release bar 22 extending along the carriage in front of the keys is mounted by arms 23 and collars 23^a upon the shaft 15, so that the 100 carriage may be released by the finger of the operator at the same time that a denomination key is depressed.

Referring to Fig. 4, it will be seen that mounted loosely upon the carriage releasing 105 rock shaft 15 between the collars 23^a are two sets of bails of graduated sizes, the bails being nested one within another, and the sets of bails being placed side by side, each bail 110 depressible independently of the others.

The largest bail in each set is numbered 24, the next 25, the next 26, and the remaining bails 27 and 28. Each bail comprises a pair of arms 32 and 33, both arms extending forwardly from the rock-shaft 15. The arms 32 are straight and parallel and mounted at letter space intervals and form a system of ten denomination stops. The denomination keys 34 are mounted in front of the stops 35 upon extensions 35 which diverge forwardly from the bail-arms, such divergence being necessary where the keys are mounted in a single row as illustrated, since the length of such row is much greater than the width of the system of stops 32. It will be seen that the stops and keys are arranged in the same order throughout the system, and that the denomination of the keys proceeds in regular order beginning at the right hand with the decimal mark and increasing to millions at the left hand end of the row. The bails in one set correspond to those in the other but are oppositely disposed, that is to say, the short arms in one set of bails are upon the left while the corresponding arms in the other set of bails are on the right of the system of stop arms. The smallest bail 28, whose stop-arm carries a key at the extreme end of the row of keys is nested within the next larger bail 27 which carries the next key; and the bail 27 in turn is nested within 26 which carries the third key and is in turn nested within 25 carrying the fourth key; the bail 25 being nested within the largest bail 24 carrying the fifth key. By means of this construction and this position of the bails, ample length of bearing in axial direction is secured even for the smaller bails, while the end system of bails is kept within a small compass. Springs 36 under the outer arms of the bails return the latter to normal positions. All except the two middle extensions 35 are branched out from the stop arms 32 between the ends of the latter as seen best at Fig. 2, so that the outer extensions when depressed may clear the adjoining stops which they overlie as at Figs. 1 and 4; the point of branching being carried gradually backward from the middle to the sides of the system, to give clearance for the extensions with relation to one another. The bracket 17 is formed at its rear edge with an upturned comb 37 to guide the bail-arms; and the front edge of the same plate 55 or bracket is also bent up to form a corresponding guiding comb 38 for the same arms.

In operation, any desired denomination key is depressed, the finger at the same time pressing down the release key 22. The carriage is then drawn along by the spring 5 until arrested by the engagement of the depressed stop 32 with a column stop 40 provided upon the framework. The denomination key and release key are then relieved of

pressure and the type keys manipulated in the usual manner, types 41 striking as usual on the front of the platen 1. The depressible release key 22 may be used for releasing the carriage for ordinary purposes, as well as during the operation of tabulating as it forms a very convenient release key. The stops 40 are adjustable along a rack 42 mounted upon the framework.

It will be seen that the keys are not only mounted at the front of the machine where they may be conveniently seen and operated, but also that they are below the line of vision. That is, the tabulating mechanism does not come between the line of writing on the platen and the eyes of the operator.

Referring now particularly to Fig. 1, it will be seen that in place of the two outer bails 24, single stop-arms 24^a are employed having forwardly divergent extensions 35 85 bearing the two middle keys 34. Said middle keys are but little offset from said arms 24^a, and hence the latter may be sufficiently guided and steadied by means of the guiding combs, so that it is unnecessary to employ bails for these keys, whereby the tabulating mechanism is somewhat more compacted and its cost somewhat reduced.

Beneath the keys is an arresting bar 43 supported by means of arms 44 extending 95 forwardly from the bracket 17. This stop-bar will prevent undue depression of the keys and consequent distortion of an injury to the extensions 35, especially at the extremities of the keyboard.

The bails 28 may in some cases be omitted and the denominational lettering upon the keys changed accordingly.

Variations may be resorted to within the scope of the invention, and portions of my 105 improvements may be used without others.

Having thus described my invention, I claim:

1. A tabulating mechanism including a set of bails of graduated sizes nested together and hinged upon a common axis, each bail consisting of a cross-bar and a pair of arms connected thereby and both hinged upon said axis, the inner arm of each pair extending forwardly from said axis and provided with a denomination-stop, and key-bearing extensions diverging forwardly from all of said stop-arms.

2. A tabulating mechanism including two sets of bails hinged upon a common axis, 120 each bail consisting of a cross-bar and a pair of arms connected thereby and both hinged upon said axis, the bails in each set being of graduated sizes and nested together, the inner arm of each pair extending forwardly 125 from said axis and provided with a denomination-stop, all of said stops being mounted at letter space intervals, the bails in one set being disposed oppositely from those in the other set, key-bearing extensions diverging 130

forwardly to the left from all of the stop-arms in one set of bails, and key-bearing extensions diverging forwardly to the right from all of the stop-arms in the other set 5 of bails.

3. In a tabulating mechanism including two sets of bails hinged upon a common axis, each bail having a pair of arms both hinged upon said axis, the bails in each set being of graduated sizes and nested together, the inner arm of each pair extending forwardly from said axis and provided with a denomination-stop, the bails in one set being disposed oppositely from those in the other set, key-bearing extensions diverging forwardly to the left from the stop-arms in one set of bails, and key-bearing extensions 10 diverging forwardly to the right from the stop-arms in the other set of bails; said extensions branching from the tops of the stop-arms at points between the ends of the latter.

15 4. A tabulating mechanism including a set of bails of graduated sizes nested together and hinged upon a common axis, each bail consisting of a cross-bar and a pair of arms connected by said cross-bar and both hinged upon said axis, the inner arm of each pair 20 extending forwardly from said axis and provided with a denomination-stop, and key-bearing extensions upon all of said stop-arms.

25 5. A tabulating mechanism including two sets of bails hinged upon a common axis, each bail consisting of a cross-bar and a pair of arms connected by said cross-bar and both hinged upon said axis, the bails in each 30 set being of graduated sizes and nested together, the inner arm of each pair extending forwardly from said axis and provided with a denomination-stop, all of said stops being mounted at letter space intervals, the bails in one set being disposed oppositely from those in the other set, and key-bearing extensions 35 upon all the stop-arms.

40 6. In a tabulating mechanism including two sets of bails hinged upon a common axis, each bail having a pair of arms both hinged upon said axis, the bails in each set being of graduated sizes and nested together, the inner arm of each pair extending forwardly from said axis and provided with a denomination-stop, the bails in one set being disposed oppositely from those in the other set, stops in the form of single arms pivoted upon said axis between said sets of bails, all of the stops being mounted at letter space intervals to form a single system, and key-bearing devices extending forwardly from said stops.

45 7. A tabulating mechanism including two sets of bails hinged upon a common axis, each bail having a pair of arms both hinged

upon said axis, the bails in each set being of graduated sizes and nested together, the inner arm of each pair extending forwardly from said axis and provided with a denomination-stop, all of said stops being mounted 50 at letter space intervals, the bails in one set being disposed oppositely from those in the other set, key-bearing extensions diverging forwardly to the left from the stop-arms in one set of bails, and key-bearing extensions 55 diverging forwardly to the right from the stop-arms in the other set of bails; said extensions branching from the tops of the stop-arms at points between the ends of the latter.

8. A tabulating mechanism including a series of nested bails, each bail having a stop and one arm of each bail being extended forwardly and provided with a key, the stops being mounted at letter space intervals, and keys being mounted in a single row in 85 front of the stops, said extended arms diverging forwardly from said bails, and means directly under the forward ends of the extensions for arresting the keys when depressed.

9. A tabulating mechanism including a bracket to attach to a carriage, a shaft upon said bracket, a series of bails nested together and all pivoted upon said shaft, stop-arms formed upon said bails and arranged at letter space intervals, forwardly diverging key-bearing arms, each of which is in the form of an extension of a bail arm, and a bar beneath the extensions and supported upon said bracket for arresting the keys.

10. A tabulating mechanism including two sets of bails hinged upon a common axis, each bail having a pair of arms both hinged upon said axis, the bails in each set being of graduated sizes and nested together, the inner arm of each pair extending forwardly from said axis and provided with a denomination-stop, all of said stops being mounted at letter space intervals, the bails in one set being disposed oppositely from those in the other set, key-bearing extensions diverging forwardly to the left from the stop-arms in one set of bails, and key-bearing extensions 105 diverging forwardly to the right from the stop-arms in the other set of bails; and means extending under the forward portions of said extensions for arresting the same.

11. A tabulating mechanism including two groups of bails, each bail comprising a cross-bar and two arms connected thereby, one of the arms on each bail forming a denomination stop, keys upon divergent arms provided upon said bails, and a stop in the form of a single arm pivoted between said 120 groups of bails, and provided with a key; all of said stops being mounted at letter-space intervals to form a single system.

12. A tabulating mechanism including two groups of bails, each bail comprising

a cross-bar and two arms connected thereby, one of the arms on each bail forming a denomination stop, keys upon divergent arms formed upon said bails, and a plurality 5 of stops in the form of single divergent arms provided upon said groups of bails and provided with keys; all of said stops being mounted at letter-space intervals to form a single system.

10 13. In a tabulating mechanism for type-writing machines, the combination of two sets of bails, said sets placed side by side, and all having a common pivotal axis of motion, the adjoining bail arms in said sets 15 forming denomination stops, and single-arm denomination stops intervening between said sets, and diverging at their key-bearing ends, all of said stops being mounted at letter-space intervals to form a single system.

20 14. In a tabulating mechanism for type-writing machines, the combination of two sets of bails, said sets placed side by side, and all having a common pivotal axis of motion, the adjoining bail arms in said sets 25 forming denomination stops, single-arm denomination stops intervening between said sets and diverging at their key bearing ends, and keys fixed upon all of said stops; all of said stops being mounted at letter-space 30 intervals to form a single system.

30 15. In a typewriting mechanism for type-writing machines, the combination of two

sets of bails, said sets arranged side by side, and all the bails having a common axis or pivot rod, the bails in both sets formed with 35 stops at letter-space intervals, and denomination stops in the form of single arms intervening between said sets and pivoted upon said rod and provided with keys; certain of the arms of said bails being provided with 40 keys, and all the keys being mounted on divergent arms and forming a single row; all of said stops being mounted at letter-space intervals to form a single system.

45 16. In a tabulating mechanism for type-writing machines, the combination of two sets of bails, said sets arranged side by side, and all the bails having a common axis or pivot rod, the bails in both sets formed with 50 stops at letter-space intervals, and denomination stops in the form of single arms intervening between said sets and pivoted upon said rod and provided with key-bearing 55 forwardly diverging extensions; certain of the arms of the bails being provided with forwardly diverging key-bearing extensions, and all the keys being mounted on diverging arms and forming a single row; all of said stops being mounted at letter-space intervals to form a single system.

HERMAN L. WAGNER.
